UNITED STATES PATENT OFFICE.

GEORGE H. RICH, OF GENEVA, ILLINOIS.

IMPROVEMENT IN MACHINES FOR SEPARATING COCKLE, &c., FROM WHEAT.

Specification forming part of Letters Patent No. **142,119**, dated August 26, 1873; application filed February 4, 1873.

To all whom it may concern:

Be it known that I, GEORGE H. RICH, of Geneva, in the county of Kane and State of Illinois, have invented certain Improvements in Machines for Separating Cockle and small Seed from Wheat, &c., of which the following is a specification:

This invention consists in employing a hollow revolving cylinder perforated with holes large enough to allow the passage of the cockle-berries, said cylinder being surrounded upon its under surface by an endless apron held up closely against the outside thereof by means of rollers, as will hereinafter more fully appear. The grain is fed into this cylinder at one end and passes out at the other by its own gravity, the cylinder being slightly inclined to insure this result. The metal composing the cylinder is made of such a thickness that the perforations, when obstructed upon the outside by the apron, form cavities of a depth just sufficient to allow the cockle-berries to lie below the inner surface of the cylinder, but so shallow that the berries of wheat which may lodge in them endwise will project in part within the cylinder, and, by the action of the body of grain in the revolution, will be swept back into the cylinder, while the cockle rides upon the apron and is discharged outside by the action of the apron, which is moved continuously by its contact with the revolving cylinder, being kept taut by the weight of the cylinder resting upon it; and the invention further consists in the method of feeding the cylinder by means of a chamber, into which the grain is led, and into which projects the mouth of the cylinder, which is furnished with a set of inclined internal vanes, acting after the manner of a screw to draw the grain gradually in.

In the accompanying drawings, which form a part of this specification, Figure 1 is a central vertical longitudinal section of the machine. Fig. 2 is a central vertical transverse section of the same. Fig. 3 is an end view of the feeding or receiving end of the cylinder, showing the inclined internal vanes. Fig. 4 is an end view of the discharging end of same.

Like letters of reference made use of in the several figures indicate like parts.

To enable those skilled in the art to make

and use my invention, I will proceed to describe the same with particularity, making use in so doing of the aforesaid drawings by letters of reference thereto.

In said drawings, A represents the perforated revolving cylinder, the perforations of which should be, as I find by experiment, about one-eighth of an inch, more or less, in diameter, where a single cylinder is employed, and it is desired that no wheat shall pass over with the cockle. The material of the cylinder should be of a thickness a little greater than one-half the largest diameter of a cockle-seed. B is the endless apron passing around the outer under surface of the cylinder in contact therewith, and breaking contact on both sides of the cylinder below the horizontal center. This apron at each side of the cylinder passes over the rollers C C, and below passes under the roller C', the three rollers being placed in a triangle. The roller C' is carried in a bearing which allows it to move vertically, so that its weight will stretch the apron and hold it firmly against the cylinder; and to insure this result I prefer to make this roller C' of metal to give it weight. D is a brush-roller, so mounted that it revolves by contact with the outer surface of the cylinder. This brush may be made stationary, if desired; but I prefer, for obvious reasons, that it should rotate, and recommend that construction. By means of this brush the perforations are kept clear of grain and débris. E is a chamber, into which the grain to be cleansed is poured. The mouth a of the cylinder enters this chamber, and, by means of the internal screw arrangement of the inclined vanes b b', draws the grain into the cylinder with a steady feed, which should be so regulated as to keep said cylinder not more than half full. F are the discharge-ports, with inclined wings to regulate the amount of discharge. G is a conveyer to carry the cockle and screenings out at the end of the machine.

The cockle and any broken bits of grain of a similar size, by the action of the revolving cylinder, finally lodge in the perforations and rest upon the apron, while the wheat-berries which may lodge there also are soon jostled out by the grain striking against such portion as may project within the cylinder, as the cavity formed by the perforation with the

apron as a floor is not deep enough to take in the entire wheat-berry. The revolution of the cylinder carries up such cockle-berries as may have lodged, and they pass over the roller and fall below to the conveyer. This peculiar action is clearly shown at Fig. 2 of the drawing. The centrifugal force of the cylinder while revolving tends to cause the discharge of the cockle from the apertures after they are free of the apron, and by the same reason tends to keep them securely in the apertures until free from the apron.

Having thus fully described the construction and operation of my invention, what I claim as new, and desire to secure by Letters Patent, is—

1. The perforated cylinder A, constructed substantially as described, in combination with the endless apron B, substantially as and for the purpose specified.

2. The chamber E, into which project the mouth or mouths a of the cylinder, in combination with said cylinder, provided with the internal inclined feeding-vanes b b', or their equivalents, substantially as specified.

GEORGE H. RICH. [L. S.]
